UNITED STATES PATENT OFFICE

EUGENE A. KUEN, OF CINCINNATI, OHIO

RADIO FREQUENCY CIRCUITS

Application filed April 7, 1927. Serial No. 181,853.

This invention is particularly designed for the utilization of a type of transformer which incorporates either two distinct secondary windings or a single secondary which is divided equally to produce in effect two secondaries.

An object is to produce a circuit in which increased sensitivity is obtained for the reception of weak or distant signals, as compared with that obtained by other circuits known to me, and in which an additional object is to obtain such increased sensitivity through means which accomplish the tuning of the circuit in a materially easier manner with less critical adjustment of the tuning instrumentalities.

These and other objects are attained in the circuit described in the following specification and illustrated in the accompanying drawings, in which:

Fig. 1 is a view illustrating in the usual diagrammatic manner a circuit embodying my invention and using single grid tubes.

Figs. 2, 3 and 4 are views upon the same lines as Fig. 1 and illustrative of my invention in different forms thereof.

Fig. 5 is a view similar to Fig. 1 but illustrative of the application of my invention to two grid tubes.

Figs. 6, 7 and 8 are views similar to Figs. 2, 3 and 4, but showing other two grid tube adaptations of my invention.

My invention as described herein is an outgrowth of the invention set forth in United States Letters Patent Number 1,606,947 which was issued jointly to me and Clarence L. Patterson upon November 16, 1926. In this patent a transformer employing two secondary windings is described. Such a transformer construction is employed in the invention I am about to describe.

I will now take up the description of Fig. 1. In this embodiment the usual antenna coupler 9 is employed, with a connection 10 to grid of the tube 11. Following this tube is the radio frequency transformer 12 which embodies two secondary windings. The primary of this transformer is connected with the plate of the first tube, as at 13, while one of the transformer secondaries is connected

with the grid of the next tube 14. The extra or additional secondary is connected backwardly to the grid of the first tube 11 through a blocking condenser 15. Then another stage is added in the form of another transformer 16 the primary of which is connected as at 17 with the plate of the preceding tube 14, with one secondary connected by connection 18 with the grid of the detector tube 19, while the other or additional secondary is connected back through a blocking condenser 20 to the grid of the preceding tube. In this embodiment the usual secondary connections with the grids of the succeeding tube are made with a joint filament return through a 65 potentiometer or a current divider 21. However, the extra or additional secondary in each transformer is merely connected at one end with the preceding tube grid through the blocking condensers 15 and 20, the opposite 70 end of each is unconnected.

Fig. 2 discloses a slight modification of the circuit, showing the two secondary transformer idea carried out a little differently as to position and connection in the circuit. Instead of the usual two winding antenna coupler I have shown a three winding or two secondary type 22 in this position. The tube 23 with which this transformer connects has its grid connected directly to one secondary winding, the other secondary winding also connecting therewith but through a blocking condenser 24. The next stage following the tube 23 also contains a transformer 25 of the two secondary type which is connected with 80 the grid of tube 26 directly through one secondary while the other secondary has connection with this grid only through a blocking condenser 27. In this embodiment I have shown the principal secondaries all having a common filament return through a 85 potentiometer 28 as in Fig. 1, but the extra secondaries, instead of having a dead end, are connected to the filament return directly.

In Fig. 3 I have shown an embodiment which is similar to that shown in Fig. 1, in the arrangement of the tubes and transformers, except that in two particulars there is a difference as to connection. One of these differences lies in the connection of the main 100

or principal secondaries as to filament return in that instead of a filament return through a potentiometer there is direct connection of each principal secondary to the filament circuit. The other of these differences lies in the connection of the dead ends of the additional secondaries as shown in Fig. 1, to the filament circuit in the same manner as are the principal secondaries.

10 In Fig. 4 I have shown diagrammatically a portion of a circuit in which a center tapped secondary is employed, the connections being in every respect identical with those shown in Fig. 3, as will be seen by inspection of the 15 two circuits.

And now we come to the two grid tube adaptations of the invention, which are disclosed in Figs. 5, 6, 7 and 8. In Fig. 5 the identical circuit as is disclosed in Fig. 1 is shown. The 20 dead ended additional secondaries of the transformers 29 and 30 are shown, but in all the tubes 31, 32 and 33 are found two grids. In this two grid tube arrangement there is however separate connection made to each 25 of the grids. One of these connections (34, 35) is from one secondary of a preceding transformer forwardly to one of the grids of a succeeding tube, while the other connection (36, 37) is made from the other secondary 30 backwardly through a blocking condenser as exemplified at 38 and 39 respectively to the other of the grids in each tube.

In Fig. 6 I have shown identically the same circuit as that shown in Fig. 2 with the exception that instead of the two secondary connections being made to the one grid, the two grid tube permits of one grid being used for each connection.

Fig. 7 shows identically the same circuits 40 as those of Fig. 3 except as to the use of a two grid tube. Here will be found the separate grids used for the two grid connections which are provided for each tube.

In Fig. 8 will be found the identical circuit 45 which I have shown in Fig. 4 except that a two grid tube has been adapted thereto.

The functioning of the circuit I have shown is no doubt quite obvious to those skilled in the art and for this reason I will not enter 50 upon a needless and lengthy technical dissertation as to the precise actions, reactions, etc., entering into the functioning of this circuit. However I will point out that the subjection 55 of all the principal secondaries to the same input and other voltage conditions will cause the other or additional secondaries to respond in the same manner through inductive action. However the action of the additional secondaries will be retarded slightly by a blocking action of the condensers interposed between them and the grids to which these secondaries are indirectly connected. This causes the amplified signal energy to be smoothed out by allowing it to be fed gradually so that the objectionable rushes of signal

energy will be ironed out as it were. The effect just described is also somewhat that of a stepping of the energy impulses impressed upon the two grids out of phase just enough to bring about a surprising clearness of tone and volume with a minimized noise and static level. This I also find to be accomplished with increased sensitivity and correspondingly increased selectivity and ease of tuning.

Having thus described my invention what I claim is:

1. In a radio frequency amplification circuit, the combination of a series of alternately associated electron emission devices and radio frequency transformers, said transformers having duplicate secondary windings connected with duplicate grids in all the devices, the connection of one of said secondary windings with one of the grids being effected through a condenser in series therewith, the connection of the other of said secondary windings with the other of the grids being effected with a condenser in parallel therewith.

2. In a radio frequency amplification circuit, the combination of a series of alternately associated electron emission devices and radio frequency transformers, said transformers having duplicate secondary windings connected with duplicate grids in all the devices, the connection of one of said secondary windings with one of the grids being effected through a condenser in series therewith, the connection of the other of said secondary windings with the other of the grids being effected with a condenser in parallel therewith, one of said condensers being of variable capacity.

In testimony whereof I have hereunto affixed my signature.

EUGENE A. KUEN.
